FIG 1

FIG 2

Frederick R. Dorr Inventor

By Owen Owen Dauphina Attorney

Patented Sept. 1, 1925.

Des. 68,093

UNITED STATES PATENT OFFICE.

FREDERICK R. DORR, OF ERIE, MICHIGAN.

DESIGN FOR A RADIATOR CAP.

Application filed April 6, 1925. Serial No. 13,038. Term of patent 7 years.

To all whom it may concern:

Be it known that I, FREDERICK R. DORR, a citizen of the United States, residing at Erie, in the county of Monroe and State of Michigan, have invented a new, original, and ornamental Design for a Radiator Cap, of which the following is a specification, reference being had to the accompanying drawing, forming a part thereof.

Figure 1 is a front view of a radiator cap showing my new design. Fig. 2 is a side view of the same.

I claim:

The ornamental design for a radiator cap as shown.

FREDERICK R. DORR.
